UNITED STATES PATENT OFFICE.

GEORGE GASCHKE, OF NEWARK, NEW JERSEY, ASSIGNOR TO AMERICAN PLATINUM WORKS, OF NEWARK, NEW JERSEY, A CORPORATION OF NEW JERSEY.

SAFETY PIN, BROOCH, AND CLASPS.

Application filed June 1, 1922. Serial No. 565,159.

To all whom it may concern:

Be it known that I, GEORGE GASCHKE, a citizen of the United States, residing at Newark, county of Essex, and State of New Jersey, have invented new and useful Improvements in Safety Pins, Brooches, and Clasps, of which the following is a specification.

The principal object of the present invention is to produce safety pins in which the tongue members may be securely locked when in an engaged position or released at will, by readily operated means.

Another purpose is to provide a pin of neat appearance, durable in nature and produced at a moderate cost.

A further aim is in the provision of a pin which may be so constructed as to present an ornamental appearance as that of a brooch or the like, without conflicting with its utility.

These several objects are attained by the novel construction, combination and arrangement of parts hereinafter described and shown in the annexed drawing, constituting an essential part of this disclosure, and in which:—

Figure 1 is a side elevational view showing an embodiment of the preferred form of pin in a closed or engaged position.

Figure 2 is an end view of the same.

Figure 3 is another like view but showing the pin in an open or released position.

Figure 4 is fragmental side view of a pin showing a slight modification in the catch construction.

Figure 5 is a transverse sectional view taken on line 5—5 of Fig. 4.

Figure 6 is a perspective view of a blank pin partially formed.

Figure 7 is a side view of a pin made from a blank similar to that shown in Fig. 6.

Figure 8 is an end view thereof.

Figure 9 is a side view showing another modification in construction.

Figure 10 is a sectional view of the same taken on line 10—10 of Fig. 9.

In the drawing, Figs. 1, 2 and 3 show a pin made from a common round resilient wire, having a sharp pointed end 15 on its straight tongue 16, the same having a coil 17 at its opposite end, said coil connecting with the bar element 18.

This bar 18 is turned angularly upward, as at 19, continued to form a loop 20, ex-

tended outward and downturned to present a bight 21, thence into an arm 22 spaced parallel to the element 19, and having a terminal eye 23 tightly closed upon the bar 18.

The pointed end 15 of the pin is contained in the bight 21 when the tongue is in an engaged position, readily entering the space between the overhanging or outstanding loop and the parallel elements back of it.

In order to hold the tongue positively from becoming disengaged a keeper is used, the same consisting of a narrow strip of thin resilient material coiled or rolled to present a band 24 encircling that part of the bar 18 between the elements 19 and 22, thence continued to form an angle element 25 the upper member 26 which is suited to engage the lowermost surface of the loop 20 under spring compression, the seat member 26 passing through the space between the arm members and being continued into an outstanding curve 27 ending in a lip 28 adapted to overlie the point of the pin.

Due to the contact of the seat element 26 and loop 20, this keeper, when in engagement, prevents the tongue from being released, as upon pressing it towards the bar it will make contact with the seat and cannot be moved out of the space 21, until the keeper is turned rearwardly on the bar, which is easily accomplished by engaging the lip 28 by a person's finger and pressing it rearwardly.

In the modification shown in Figs. 4 and 5 the tongue 30 has a point 31 and may be connected to the bar 32 by a coil or plain band as preferred.

The end of the bar is provided with a pair of integral spaced arms 33 and 34, extended towards the point of the tongue, bent forward and downward forming collectively a bight or space 35 and joined by a bar 36.

The keeper is made from material similar to that described, and has a closed loop or eye 37 encircling that part of the pin bar 32 between the arms.

One end of the keeper is formed into an outreaching angle 38, turned sharply to form a seat 39, adapted to engage the bar 36, the other part 40 of the keeper extending at 105 substantially a right angle to the seat 39 and then being curved outwardly to constitute a loop 41, which, when in an engaged position, approximately fills the space between the arms 33 and 34 at the top, its ex- 110

treme edge nearly touching the bar 36, locking the pin when entered in the space 35 until it is released by pressing the keeper rearwardly.

5 Another modification, shown in Figs. 6, 7 and 8 discloses a pin or brooch of ornamental nature entailing the same general characteristics but of slightly different construction.

10 In this type the pin tongue 45 is provided with a pointed end 46 and connected by a semi-circular bend 47 with the pin bar 48, the latter being relatively thicker and considerably wider than the tongue to provide 15 a surface capable of being embossed, engraved or otherwise superficially ornamented.

The outer end of the bar is bifurcated to produce two prongs of unequal length, respectively 49 and 50, the former, shorter prong being bent closely re-entrant and the other prong 50 bent to form the side and bar elements of a loop 51 in the bight 52 of which the end of the pin tongue is received 25 in the manner previously described, the extremity of the prong being soldered firmly to the inner side of the pin bar 48.

The keeper is in all respects like that first described, consisting of an eye 53 engaging 30 the shorter prong 49 to turn freely on it and is provided with a spring seat 54 to engage the loop 51, the keeper terminating in a slightly extending lip 55.

A further variation in construction is disclosed in Figs. 9 and 10, in which the pin tongue 60 is of circular cross section terminating in a point 61 at one end and joined by a curve 62 to the pin bar 63, here indicated as of rectangular cross section.

40 Said bar 63 is stamped from sheet metal to produce an integral angular element 64 expanded at its outer end 65 and containing a relatively narrow slot 66 enlarged in the expanded portion 65, which is turned over 45 upon the narrower element 64, a space 67 for the reception of the tongue point intervening.

The keeper in this type may be blanked from sheet metal to form an eye 68 enclosing 50 that part of the bar at the bottom of the slot 66, formed with an angular extension 69 adapted to make contact with the down-turned edge of the element 65, presenting a recess 70 thereabove suited to make contact 55 with the tongue near its point and having a nail nick 71 on its outer, upper edge to be used in detaching the keeper in releasing the pin.

From the foregoing it will be seen that a 60 type of pin or brooch has been disclosed in which the point is efficiently protected and

the tongue positively locked, while the manner of operation is clearly apparent.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:—

1. A pin or brooch comprising a bar, a spring tongue formed therewith, a U shaped loop integral at the end of said bar extending towards the point of said tongue, said loop being bent to produce a lateral hook adapted to engage the tongue, a plate keeper hinged to said bar between the side elements of said loop, an angular extension on said keeper adapted to engage said hook to prevent the removal of the tongue, said extension also maintaining the keeper in engaged position, and a projection on said keeper by which it may be disengaged.

2. A pin or brooch comprising a relatively wide bar adapted to be ornamented, an attenuated spring tongue joined at one end thereof, a catch for the tongue at the other end of said bar, said catch being composed of a pair of members fixed to the bar, joined at their extremities and bent in the manner of a hook, a keeper pivoted to swing between the side members of said catch, a resilient element carried by said keeper suited to engage the connection between the said side members, said resilient element closing the passage to the looped portion of said catch, a loop formed with said keeper to pass over the entered tongue, and means on said loop whereby the keeper may be disengaged.

3. A pin comprising a bar having a resilient tongue and a U shaped loop disposed in a plane parallel to said bar, said loop being turned re-entrantly at the side of the outer end of said bar to receive the tongue, said elements being integrally formed, and a plate keeper hinged to the bar portion of the pin between the side elements of said loop, said keeper having a curved portion adapted to resiliently engage said tongue and an angular element by which it may be released therefrom.

This specification signed and witnessed this sixteenth day of May, 1922.

GEORGE GASCHKE.
